CARRYING IRON

Joseph C. Chenette, Flat Rock, Mich.

Refiled for abandoned application Serial No.
111,791, November 20, 1936. This application
July 12, 1939, Serial No. 284,020

7 Claims. (Cl. 294—15)

This application is a re-file of abandoned application Serial No. 111,791, filed November 20, 1936.

This invention relates to carrying irons and the object of the invention is to provide an iron which is sheathed in rubber and shaped for use in carrying heavy articles having no hand holds for carrying.

One of the particular objects of the invention 10 is to provide a carrying iron for carrying such articles as refrigerators, stoves, gas ranges, circulating heaters, heavy boxes, modern furniture, and other similar articles and arranged so that the carrying iron will not mar the finish of the 15 article being carried.

A further object of the invention is to provide a carrying iron having a foot for engagement beneath the article to be carried and having a curved bearing portion arranged to engage the 20 wall of the article and a handle extending from the bearing portion by means of which the article may be lifted.

A further object of the invention is to provide a carrying iron sheathed in rubber to provide 25 firm hand holds and also to prevent marring the finish of such articles as porcelain enameled refrigerators, gas ranges and circulating heaters and furniture.

Another object of the invention is to provide a 30 carrying iron arranged to be made up in pairs, each pair consisting of a right and left iron adapted to be applied to the article being lifted and having extending hand hold portions whereby the article may be very easily carried.

These objects and the several novel features of 35 the invention are hereinafter more fully described and claimed and the preferred form of construction by which these objects are attained is shown in the accompanying drawing in which—

Fig. 1 is a perspective view showing the carrying irons as applied to a refrigerator for carrying.

Fig. 2 is a perspective view showing both the right and left irons.

Fig. 3 is an enlarged section taken on line 45 3—3 of Fig. 2.

The iron comprises a metal bar 1 shown more particularly in Fig. 1 having a foot portion 2 provided with an upturned end 3. At the top an arcuate bearing member 4 extends from the 50 member 1 on the same side as the foot 2 and is provided with an arcuate face 5 as shown in the several views. The hand hold members 6 are each a press fit in an aperture provided therefor in the bearing member 4 as will be understood from Fig. 3 and when so fitted the hand hold

member is also welded in place in the member 5 and the end of the hand hold member 6 is ground off on the same radius as the remainder of the arcuate surface 5 of the bearing member 4. After being made up in this form, the entire 5 device is covered with a rubber sheath 7 shown more particularly in Fig. 3 and this rubber sheath covers all of the metal parts so that only the rubber sheath is seen in the completed article.

In operation, the right and left irons are used 10 as a pair as shown in Fig. 2. The iron shown at the left of Fig. 2 may be applied to a foot 2 beneath the leg of the refrigerator shown in Fig. 1. The carrying iron shown at the right of Fig. 2 is then applied in the same manner to 15 the other side of the refrigerator so that the two hand holds extend outwardly toward the person to carry the article and in a convenient position for such carrying.

In this connection, it will be noted that the 20 curved face 5 of the bearing member 4 which is covered with rubber engages against the wall of the refrigerator and this curved face 5 provides 25 a bearing against the wall of the article being carried even if the wall is set back from the base or forward therefrom, the radius 5 allowing for line contact between the bearing member and the article being carried. This arcuate bearing surface also allows the foot ends 2 to be engaged 30 further toward the center of the article being carried, if desired, and will still maintain the line contact. A refrigerator of this type may be readily carried by two persons by applying one 35 pair of irons to one side of the box for one 40 person to lift with and by applying another pair of irons to the other side of the box for the other person to lift with. By means of the rubber covered curved bearing surface 5, the finish of 45 the article being carried will not be marred and the carrying irons may be used in carrying fine pieces of furniture, porcelain enameled articles or other devices having a surface which will damage easily. This prevents loss through cracked porcelain finishes and allows refrigerators and other articles to be moved about in a 50 factory or in a store without damage to the finish.

The arrangement of the shaped metal bearing member extending at a right angle to the 55 end of the bar and on the same side as the foot and with an extended handle member made rigid to and extending at a right angle from the bearing member, forms a compound axis 55

bringing about a clamping action between the foot and bearing member thus making the carrying iron rigid to the article when an upward force is applied in lifting the same. Thus, when 5 a force is applied at the handles, the weight of the article to be lifted is centralized and prevents top heaviness and slippage of the carrying irons from the article to be moved.

It is also possible to make the bearing member 10 adjustable in a slot in the bar to vary the position of the bearing member for carrying different articles.

From the foregoing description it becomes evident that the device is very simple and efficient 15 in operation, is practically a unitary structure when completed and sheathed with rubber, is very useful in stores and factories for moving or carrying articles about and provides a device which accomplishes the objects described.

20 Having thus fully described my invention, its utility and mode of operation, what I claim and desire to secure by Letters Patent of the United States is—

1. In a carrying iron, a metal bar formed to 25 provide a hook at one end, a bearing member extending from the opposite end of the bar and on the same side of the bar as the hook, said bearing member having an arcuate face on one side arranged to engage the article being carried, a hand 30 hold member extending from the opposite side of the bearing member and a continuous rubber sheath extending over all parts of the carrying iron.

2. In a carrying iron, a metal bar formed to 35 provide a hook at one end, a bearing member extending at a right angle from the opposite end of the bar and on the same side of the bar as the hook, said bearing member having an arcuate face on one side arranged to engage the article

being carried and a hand hold member extending from the opposite side of the bearing member.

3. A carrying iron comprising a longitudinal bar having an inturned foot at the lower end, a 5 bearing member extending inwardly from the top of the bar on the same side as the foot, the bearing member having a curved face on one side and a hand hold member extending outwardly at a right angle from the bearing member on the side opposite the curved face. 10

4. A carrying iron comprising a metal bar having an inturned foot at one end, a bearing member extending from the opposite end of the bar, said bearing member having a rounded face on one side and a hand hold member extending outwardly from the bearing member. 15

5. A carrying iron comprising a metal bar having an inturned foot at one end, a bearing member extending at a right angle from the opposite end of the bar on the same side as the foot, a 20 handle member extending from the bearing member and a rubber cover forming a non-marring sheath for said device.

6. A carrying iron comprising a metal bar having a hook at one end, a bearing member extending at a right angle from the same side of the bar as the hook, the hook being arranged to be engaged beneath an article to be carried and the bearing member being arranged to engage against the side of said article and a hand hold member 30 extending from said bearing member. 25

7. A carrying iron comprising a metal bar having an inturned foot at one end, a bearing member extending from the opposite end of the bar in the same plane as the foot and a handle member 35 extending from the bearing member transversely to the plane of the foot and bearing member.

JOSEPH C. CHENETTE,
